FIG. 1.

FIG. 2.

INVENTOR
WILLIAM P. FAY.

By Charles McNeill Attest.

UNITED STATES PATENT OFFICE

102,749

DESIGN FOR A GOLF TEE OR SIMILAR ARTICLE

William P. Fay, Chicago, Ill.

Application June 1, 1936, Serial No. 62,938

Term of patent 3½ years

To all whom it may concern:

Be it known that I, William P. Fay, a citizen of the United States and a resident of the city of Chicago, in the county of Cook and State of Illinois, have invented a new, original, and ornamental Design for a Golf Tee or Similar Article, of which the following is a specification, reference being had to the accompanying drawing forming a part thereof.

On the drawing:

I claim:

The ornamental design for a golf tee or similar article as shown.

WILLIAM P. FAY.
